GUIDE FOR MOVING WEBS OR SHEETS

Lynn F. Cooper, Neenah, Wis., assignor, by mesne assignments, to Gilbert & Nash Company, Menasha, Wis., a corporation of Wisconsin

Application April 6, 1949, Serial No. 85,927

12 Claims. (Cl. 271—2.6)

1

This invention relates to guides for moving webs or sheets of material and more particularly to a roll type of guide for a moving web where-in a fluid operated mechanism is utilized to obtain shifting of the guide roll.

Many devices have been proposed and have been used for maintaining a moving web of paper, regenerated cellulose, felt etc. which is being carried forwardly on a plurality of rolls from sliding side to side on the rolls. In paper manufacture such devices are known as wire guides or felt guides and most generally comprise a guide roll which is journaled on one side of the moving web in a swivel bearing suitably mounted on a support and journaled on the other side of the web in a bearing housing which is adapted to be moved backwardly and forwardly in a direction parallel to the movement of the web so as to change the angular position of the roll with respect to the web and hence move the web a corrective distance one way or another in order to maintain the edge of the web or felt moving in substantially a straight line. Guides operating on this general principle were known quite early as shown in U. S. 711,139. This general principle may be applied for guiding webs whether the guide roll is serving as a feed roll of the material being guided, an end roll in an endless belt or simply as a guide roll having a controlling contact with a moving web at some point intermediate its path of travel. In many applications the guide roll functions at a point where the web is moving in a horizontal plane but the same principle is applicable for keeping a web moving in a vertical plane from shifting laterally so long as the guide roll has a controlling contact with the web. Furthermore essentially the same principles may be employed by shifting the guide roll transversely, particularly where the guide roll is the feed roll.

In paper manufacture the present web or wire guides utilize a palm to contact the edge of the moving web and any tendency for the web to shift laterally will cause a movement of the palm which in turn will cause through mechanical means a corrective movement of the guide roll. Though these mechanical devices have been very dependable, as machine speeds increase it has been found that their correction time is such that serious deviations in the path of travel of the web may result before the correction takes place. Furthermore because of the slow response time in the present mechanical devices a great deal of "hunting" is experienced with the present guides.

It is one of the objects of this invention to

2

provide a web or wire guide which will maintain the direction of a moving web with a greater degree of accuracy than has heretofore been possible. It is a further object to provide a guide with a sufficiently rapid response time to substantially reduce any "hunting." It is still a further object of this invention to provide a guide capable of handling very long and heavy guide rolls with a high degree of sensitivity, and it is still a further object of this invention to provide a guide wherein a minimum of moving mechanical parts insures a minimum of error due to variations in wearing surfaces; and still another object to provide a guide in which the movement of the guide roll is accomplished by the application of hydraulic pressures and it is yet a further object that the power for operating the guide be generated by the moving web which is being guided.

20 To accomplish the aforesaid objects, and other objects which will be apparent from the description of my invention, I provide a guide which comprises means for indicating lateral movement of the web or wire to be guided which indications are transferred to a valve mechanism which controls a source of high pressure fluid. The valve mechanism is adapted to direct the fluid to one or the other side of a double acting piston in order to effect shifting of the guide and thus the guide roll which is journaled at one end in the guide. In my guide the high pressure hydraulic fluid is preferably supplied by a rotary hydraulic pump which is driven by the guide roll, hence, the hydraulic fluid pressure is independent of external demands.

35 My invention will be better understood by reference to the attached drawings illustrating a preferred embodiment. In the drawings like numerals have been used to refer to like parts in each of the figures.

40 Figure 1 is a plan view showing my guide mechanism in operative association with a guide roll and a web traveling across said roll.

Figure 2 is a rear elevation.

45 Figure 3 is a front elevation of my guide mechanism independent of the roll with parts broken away.

Figure 4 is a vertical section taken along the line 4—4 of Figure 1.

50 Figure 5 is an enlarged fragmentary view of the section of the hydraulic valve in my guide mechanism as shown in Figure 4.

Figure 6 is an enlarged fragmentary sectional view of the hydraulic valve taken along the line 6—6 of Figure 5.

55

Figure 7 is a view similar to Figure 6 showing the valve in an opposite position to that in Figure 6.

Figure 8 is an enlarged fragmentary sectional view taken along the line 8-8 of Figure 6 showing the valve position for moving the guide mechanism in one direction.

Figure 9 is an enlarged fragmentary sectional view taken along the line 9-9 of Figure 7 showing the valve position for moving the guide mechanism in the opposite direction to that in Figure 8.

Figure 10 is a view similar to Figures 8 and 9 showing the position of the valve when the mechanism is in neutral position.

Referring to Figures 1 through 4 my improved guide 1 is shown in operative position with respect to a guide roll 2 over which is traveling a web or pellicle 3. The guide roll as is conventional is supported at one end (not shown) in a suitable rotatable bearing whereby the angular position of the guide roll 2 may be changed by movement of my guide in a direction parallel to the travel of the web 3. The contact between the web and the guide roll is controlling contact whereby this change in angularity will effect lateral or sideways displacement of the web 3.

The guide comprises a housing 4 which is rotatably mounted on a carriage or saddle 5. The saddle is slideably supported on a frame 6 which in turn is mounted through suitable screws 7 and 8 directly to a paper machine or to some other permanent supporting surface 9. The housing 4 is divided by a partition 10 to provide a bearing section 11 and a hydraulic section 12. Within the bearing section 11 is a suitable radial bearing 13 of the ball bearing type in which is journaled a spindle 14 suitably coupled through a flange coupling 15 to the guide roll 2. A sealing ring 16 seals the bearing section against leakage and a retaining nut 17 is mounted on the end of the spindle 14 in order to maintain the position of the spindle with respect to the bearing. The use of the flange coupling 15 permits rapid installation and repair without necessitating the tearing down of the guide proper.

Also forming a part of the guide mechanism are means for indicating the lateral position of one edge of the web 3 which means comprises a palm 20 which is pivotably mounted on the end of a bracket 21. The bracket 21 is slideably supported on a second bracket 22 which in turn is mounted on the saddle 5 in slide 23. A slideway 24 is provided in bracket 22 and a hand operated clamp 25 cooperates with the slideway to permit the extension or contraction of bracket 21 and bracket 22.

To effect pivotal mounting of the palm 20 a shaft 26 is journaled in bearing 27 formed at the upper end of bracket 21. A collar 28 on the upper end of the palm 20 is fixed to the shaft as by a press fit or a set screw. At the other end of the shaft is suitably fixed a crank 29 upon which is carried a weight 30. The weight 30 serves to urge the palm inwardly towards the web and hence maintain contact between the palm and the edge of the web at all times. The sensitivity of the palm may be varied by changing the position of the weight 30 along the crank 29. Movement of the palm 20 is transmitted through a system of linkages, including crank 29, rods 31 and 31a, bell crank 32, pivotably mounted on the upper end of the bracket 22, rod 33, pivoted lever 34, and arm 35, to a valve 36. The arm 35 is fixed to the valve stem 37 by set screw 38.

whereby the valve stem is rotated by linear movement of the linkage system. Weight 30 and a clamp 39, joining rods 31 and 31a, provide the power for rotating the valve when the palm 5 moves inwardly to follow the web or sheet.

Valve 36 serves to direct high pressure hydraulic fluid, issuing from a hydraulic pump 40 through discharge conduit 41 to the valve inlet 42, through either conduit 43 or 44 to one side or the other of a double acting piston 45, depending upon the direction called for by the movement of the palm. The piston 45 moves in a cylinder 46 and is carried upon a rod 47 which in turn is mounted on the bifurcated ends of arms 48 and 49 forming a part of saddle 5.

The saddle 5 is supported on roller bearings 50 which are retained in a pair of parallel races 51 and 52. A pair of side plates 53 and 54 secured to the frame 6 by screws 55 form one side of each of the races. The ends of the races are closed in part by felt lined plates 56 and 57. The plates 53 and 54 each have an inwardly extending flange 58 and 59 respectively which overlie a portion of the saddle and thus serve to retain it in assembly with the frame 6.

In order to obtain rotation of the housing 4 on the saddle so that changes in angularity of the guide roll will not cause any binding or distortion within the bearing, the housing is carried on a ball thrust bearing 60 set in the upper face 61 of the saddle 5. A pilot 62 rotatably set in a hole 63 in the saddle 5 and secured to the base of the housing by a screw 64 serves to hold the housing and the saddle in alignment. The hole and pilot are formed with two diameters, so that the pilot also serves to retain the saddle and housing assembled. A sealing and dust ring 65 protects the ball bearing ring.

The double acting piston 45 whereby movement of the saddle is effected may be of any conventional type. The one shown comprises a main head 70 having a pair of leather washers 71 and 72 on each side thereof and retaining plates 73 and 74 next to the washers. The whole assembly is clamped between a shoulder 75 formed on one half of rod 47 and a flange 76 formed on another half of rod 47. The two halves are threadedly coupled together at 77. The opposite ends of rod 47 are secured in slots 78 and 79 in arms 48 and 49 by retaining pins 80. The cylinder 46 is closed at each end by packing gland comprising gland nut 81, packing 82, and packing pressure nut 83.

Referring now more specifically to the hydraulic mechanism of my guide, the hydraulic section 12 of the housing 4 serves as a reservoir for the fluid, which is preferably oil. A drain plug 90 and a vent plug 91 are provided for draining and filling. The pump 40 is mounted within section 12 in the partition 10 and extends into the bearing section 11 of the housing. In this section the rotor spindle or shaft 92 of the pump extends into a bore hole 93 in spindle 14 and is keyed against rotation by key 94. Inlet 95 of the pump extends down near the bottom of the reservoir.

The fact that the pump is driven by the guide roll is one of the important features of my guide. In prior guides hydraulic pressure from a source outside the guide has been used, such as main water pressure, and in a plant the variations in this pressure would cause substantial variations in the response of the guide. In my guide the pressure of the pump is proportional to the speed of the guide roll hence the faster the web travels the faster is the corrective response of the guide.

This is obviously very desirable. A further advantage of this feature of my guide is that it will always operate so long as the web is moving whereas in guides relying on external power, whether it be hydraulic or electrical, the guide may be shut down while the paper machine continues to run.

I prefer, however, to limit the maximum pressure of the fluid to insure the best operation of my system at high speeds. This is accomplished by a pressure relief valve 100 connected to the conduit 41. The relief or by-pass valve may be of the conventional type including a ball 101 and spring 102 retained in a bore hole 103 by an adjusting nut 104. Inlet 105 connects the valve to conduit 41 and outlet 106 discharges back to the reservoir. When the pressure in conduit 41 exceeds the compressive force of the spring as determined by the position of the adjusting nut, a portion of the oil is by-passed around the control valve 36 and returned to the reservoir.

The valve 36 comprises a cylindrical valve body 110, preferably of metal, connected to valve spindle 37 closely fitted within a casing or well 111. The body 110 is vertically supported by a ball bearing 112 set in an enlarged part 113 of the well by means of a snap ring 114 on the spindle 37 which is pressed into the body 110. Retaining nut 115 holds the assembly in place. It should be noted that no packing is used in my valve thus insuring the maximum sensitivity. This is made possible by the structure of my valve to be described.

The valve body 110 has two annular grooves 116 and 117 therein forming a land or ridge 118 therebetween. There is an axial bore hole 119 extending from the bottom of the body upward to groove 116. A radial port 120 connects groove 116 to bore 119. The valve body fits closely in the well, but not necessarily so close as to prevent leakage between the outer surfaces of the valve body and the walls of the well 111. Because of this the bottom of the well 111 extends below the body forming an outlet chamber 121 which is connected to the reservoir by conduit 122. Any leakage between the body 110 and walls will tend to run down into chamber 121. If, however, due to the pressure of the fluid, it moves upwardly, it will be trapped in groove 116 and return to chamber 121 through port 120 and bore 119.

The body 110 is positioned so that conduit 41 discharges into annular groove or chamber 117 thus the valve body is not subject to any directional pressure which would tend to cause binding.

The annular groove 117 may be brought into communication with conduit 43 and 44 which lead to the piston 45 through ducts 125 and 126 and ports 127 and 128 respectively. (See Figures 6 and 7.) The ducts are cut in the casing and the ports are drilled in the ridge 118 of valve body 110. A second pair of ports 129 and 130 drilled in the land 118 connect annular groove 116 with ducts 125 and 126 respectively. By reference to Figures 8, 9, and 10 it will be seen that pair of ports 127 and 130, and pair of ports 128 and 129 are disposed diametrically oppositely about the periphery of the land 118. It will further be noted that ports 127 and 129, and 128 and 130 are radially set only a few degrees apart. Preferably they are spaced just far enough to permit a portion of the land between them to shut off the ducts 125 and 126, this position

being a neutral position represented in Figure 10. In this regard in order to protect the valve from over-traveling its limiting positions shown in Figures 8 and 9 stops 135 and 136 are provided to limit the arm 35.

Because the palm may move through a far greater distance than that represented by the movement of the crank between the stops, I provide in link 33, a safety device 137 which will absorb movement of the palm without transmitting that movement to the valve. This device simply comprises a housing 138 in which is placed a compression spring 139. One part of link 33 is secured to the housing by a set screw 140 and the other end of link 33 acts as a plunger 141 within the housing. This plunger is held in the housing by nut 142 and is adapted to push against the spring in one direction to effect movement of the valve until arm 35 reaches stop 136 and then further movement of the palm will only serve to compress the spring thus protecting the valve.

In the operation of my guide the web 2 passes over the guide roll 3 and rotates the same, the web being driven by other rolls not shown. Rotation of the roll 2 in turn rotates spindle 92 of the pump 40 whereby a source of fluid under high pressure is generated. If the web is traveling in a straight line the palm 20 will not move and the linkages adjusted so that valve 36 will be in the neutral position shown in Figure 10. In this neutral position the outlet from the pump in conduit 41 will flow into annular chamber or groove 117 and when this is filled the balance of the flow will pass through the relief or by-pass valve 100. When the web shifts laterally in a direction away from the guide the palm will move inwardly under the influence of weight 30 which in turn will cause a rotation of the valve 36 to the position shown in Figures 6 and 8. In this position oil from groove 117 will pass upwardly through port 127 and out through duct 125 and conduit 43 into the cylinder 46. Oil in the opposite side of the cylinder will be forced upwardly through conduit 44 and through duct 126 and port 130 in the valve 36 into annular groove 116. From this groove 116 the oil will be discharged back to the reservoir through port 120 and bore hole 119 leading to conduit 122. This pressure on the piston 45 will cause movement of the piston and hence the saddle 5. Since housing 4 is mounted on the saddle, it will move in a straight path which in turn will give an angular position to the guide roll sufficient to cause the moving web to return back to its proper position.

It is an important feature of this invention that the oil returning to the valve 36 is under approximately the same pressure as the oil entering the valve hence the valve is under a balanced pressure. Furthermore the entering oil as well as the returning oil are both supplied to annular chambers in the valve which further assists in maintaining the valve under a balanced pressure. By balancing the pressures any binding action when operating at high pressures is eliminated which would otherwise greatly reduce the sensitivity of the guide.

If the web 2 shifts in the opposite direction causing the palm to move rearwardly then the valve will be turned to the position shown in Figures 7 and 9 and the piston will be driven in the opposite direction in the manner described above to apply correction.

The above described guide is capable of con-

trolling a web travelling at any commercial speed with smooth continuous action. The guide may be used in a paper machine which operates at speeds of 250 feet per minute to as high as 3000 feet per minute without adjustment except for a possible change in the setting of the pressure relief valve. This performance is unheard of with mechanical guides now being used. It is necessary in these guides to change gear ratios when making any substantial change in machine speed.

Many other modifications of my invention will occur to those skilled in the art, as for example the use of other fluids such as air or other gas instead of liquids, as oil or water, or the shifting of the roll support vertically, or transversely of the web, hence no limitations are intended by the above described specific example except such as are contained in the following claims.

I claim:

1. An apparatus adapted to laterally shift a moving web by movement of a guide roll comprising a spindle for said guide roll, a bearing for said spindle, a housing for said bearing, a frame, means slideably supporting said housing on said frame, a double acting piston in a cylinder connected to said housing, a rotary hydraulic pump mounted in said housing, means coupling the shaft of said pump to said spindle, a reservoir in said housing, a valve, conduits connecting said valve to said pump and to each side of said piston, means for operating said valve in response to a lateral shift in said web whereby fluid may be directed from said pump to one side of said piston, and means in said valve for returning fluid on the other side of said piston from said cylinder to said reservoir.

2. The apparatus of claim 1 wherein said valve comprises a casing, a valve body rotatably supported in said casing, a valve inlet, a valve outlet, ducts in said casing connected to said conduits leading to said piston, ports in said valve body adapted to connect said valve inlet to said ducts, ports in said valve body adapted to connect said valve outlet to said ducts, a spindle connected to said valve body, and wherein said means for operating said valve in response to a lateral shift in said web rotates said spindle whereby said inlet is brought into communication with one or more of said ducts, and said outlet is brought into communication with the other of said ducts.

3. In combination, means for moving a web of material, a guide roll, means for rotatably supporting said guide roll at its ends in contact with the web whereby movement of the web rotates said guide roll, means for shifting one of said roll support means including a fluid motor, and a fluid pump, means whereby rotation of said guide roll drives said pump, and means under control of said web for controlling the fluid flow from said pump to said motor whereby said guide roll support is shifted so that said guide roll acts as a guide.

4. In combination, means for moving a web of material, a guide roll, means for rotatably supporting said guide roll at its ends in contact with the web whereby movement of the web rotates said guide roll, means for shifting one of said roll support means including a fluid motor and a fluid pump, means connecting said pump and said guide roll whereby said pump is driven by rotation of said guide roll, and means responsive to lateral shifting of said web for controlling the fluid flow from said pump to said motor

whereby said guide roll support is shifted so that said guide roll acts as a guide.

5. In combination, means for moving a web of material, a guide roll, means for supporting said guide roll at its ends in contact with the web whereby movement of the web rotates said guide roll, means for shifting one of said roll support means including a rotary hydraulic pump and a hydraulic motor, means connecting said pump and said guide roll whereby said pump is driven by rotation of said guide roll and means responsive to lateral shifting of said web for controlling the liquid flow from said pump to said motor whereby said guide roll support is shifted so that said guide roll acts as a guide.

6. In combination, means for moving a web of material, a guide roll, means for rotatably supporting said guide roll at its ends in contact with the web whereby movement of the web rotates said guide roll, said means at one end including a frame, a housing slideably mounted on said frame, a bearing mounted in said housing and a spindle mounted on said roll and journaled in said bearing, means for shifting said housing relative to said frame including a fluid pump mounted in said housing and a fluid motor, means connecting said pump and said spindle whereby said pump is driven by rotation of said guide roll and means responsive to lateral shifting of said web for controlling the fluid flow from said pump to said motor whereby said guide roll support is shifted so that said guide roll acts as a guide.

7. In combination, means for moving a web of material, a guide roll, means for rotatably supporting said guide roll at its ends in contact with the web whereby movement of the web rotates said guide roll, said means at one end including a frame, a housing slideably mounted on said frame, a bearing mounted in said housing and a spindle mounted on said roll and journaled in said bearing, means for shifting said housing relative to said frame including a rotary fluid pump mounted in said housing and a fluid motor mounted in said frame, means connecting the shaft of said pump and said spindle whereby said pump is driven by rotation of said guide roll, and means responsive to lateral shifting of said web for controlling the fluid flow from said pump to said motor including a palm and a fluid valve between said pump and said motor operable by said palm whereby said guide roll support is shifted so that said guide roll acts as a guide.

8. In combination, means for moving a web of material, a guide roll, means for rotatably supporting said guide roll at its ends in contact with the web whereby movement of the web rotates said guide roll, said means at one end including a frame, a housing slideably mounted on said frame, a bearing mounted in said housing and a spindle mounted on said roll and journaled in said bearing, means for shifting said housing relative to said frame including a rotary hydraulic pump mounted in said housing and a double acting hydraulic piston mounted in said frame and connected to said housing, means connecting said pump and said spindle whereby said pump is driven by rotation of said guide roll and means responsive to lateral shifting of said web including valve means for directing high pressure fluid from said pump to one or the other side of said piston whereby said guide roll support is shifted so that said guide roll acts as a guide.

9. In combination, means for moving a web of material, a guide roll, means for rotatably supporting said guide roll at its ends in contact with

the web whereby movement of the web rotates said guide roll, said means at one end including a frame, a housing slideably mounted on said frame, a bearing mounted in said housing and a spindle mounted on said roll and journaled in said bearing, means for shifting said housing relative to said frame including a rotary hydraulic pump mounted in said housing and a hydraulic double acting piston mounted in said frame and connected to said housing, means coupling said pump and said spindle whereby said pump is driven by rotation of said guide roll and means responsive to lateral shifting of said web including a valve for directing liquid from said pump to one or the other side of said piston whereby said guide roll support is shifted so that said guide roll acts as a guide.

10. An apparatus adapted to support and laterally shift at least one end of a guide roll in contact with a moving web in response to a lateral shift of the web whereby said guide roll acts as a guide comprising a frame, a housing slideably supported on said frame, a bearing in said housing for receiving an end of the guide roll, a fluid motor in said frame connected to said housing, a rotary fluid pump mounted in said housing, means for coupling the shaft of said pump to the guide roll, and means for directing fluid from said pump to said motor in response to a lateral shift in said web.

11. An apparatus adapted to laterally shift a moving web by movement of a guide roll comprising a spindle for said guide roll, a bearing for said spindle, a housing for said bearing, a frame, means slideably supporting said housing on said frame, a piston in a cylinder in said frame connected to said housing, a rotary hydraulic pump mounted in said housing, means coupling the shaft of said pump to said spindle, valve means connecting said pump to said cylinder,

means for operating said valve means in response to a lateral shift in said web whereby fluid may be directed from said pump to said cylinder.

12. An apparatus adapted to support and laterally shift at least one end of a guide roll in contact with a moving web in response to a lateral shift of the web whereby said guide roll acts as a guide comprising a housing, a frame, means slideably supporting said housing on said frame, a bearing in said housing for receiving an end of the guide roll, a fluid motor in said frame connected to said housing, said motor comprising a piston movable in a cylinder, a rotary fluid pump mounted in said housing, means for coupling the shaft of said pump to said guide roll, a reservoir in said housing, a valve, conduits connecting said valve to said pump and to said cylinder, means for operating said valve in response to a lateral shift in said web whereby fluid may be directed from said pump to one side of said piston, and means in said valve for returning fluid on the other side of said piston from said cylinder to said reservoir.
